UNITED STATES PATENT OFFICE.

THOMAS M. BALES AND SILAS O. LEESON, OF DUBLIN, INDIANA; SAID BALES ASSIGNOR TO ALBERT SOUTHWORTH, OF SAME PLACE.

DOOR-BELL.

SPECIFICATION forming part of Letters Patent No. 351,245, dated October 19, 1886

Application filed June 23, 1886. Serial No. 206,042. (Model.)

To all whom it may concern:

Be it known that we, THOMAS M. BALES and SILAS O. LEESON, citizens of the United States, residing at Dublin, in the county of Wayne and State of Indiana, have invented 5 certain new and useful Improvements in Door-Bells; and we do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of this invention and is a vertical section. Fig. 2 is a front view, partly broken away to show the mechanism.

Our invention relates to door-bells; and it 20 consists in the construction and novel combination of parts, as hereinafter described, and pointed out in the claims.

Referring by letter to the accompanying drawings, A designates a board or base, to 25 one face of which the door-bell B and the mechanism for operating the striker are secured, ready for attachment to the inner face of any door where it may be desirable or necessary to use the door-bell. The board A is 30 secured in place by screws passed through said board into the inner face of the door at any suitable point or location.

The striker mechanism comprises two bearing-plates, D E, one of which, D, is a flat plate 35 of sheet metal, and the other, E, is an angular plate or casting having flanges F, which rest against the base-plate D, screws G G' being passed through both plates D E to secure them in place on the board A. The spindle H, on 40 which a spur-gear, I, is fixed between the bearing-plates D E, projects through the board A, and also through a seat made for it through the door, and this spindle H is provided with a knob, J, which is secured thereon by a set-screw, K.

The striker-arm L is constructed after the style of a pendulum, and is connected at its upper end to the shaft M of the pallet N,

which engages the spur gear or scape-wheel I. The striker-arm L is secured near the 50 rear end of the shaft M, and is bent near its upper end toward the board A, and passes down behind the edge of the alarm-bell B, or between the edge of the bell B and the board A, sufficient space being left for the striker- 55 arm to vibrate freely.

At its lower end the striker-arm L is provided with a rod or elongated hammer, Q, which, when the striker-arm is oscillated or vibrated, moves in the arc of a circle, so that 60 the flat ends of the hammer will strike the inner face of the alarm-bell fairly, and will not make a sliding blow thereon, thereby insuring a clear sound when the alarm-bell is struck by the hammer.

65 The alarm-bell B is secured against the outer end of a sleeve, R, by a screw, S, passed through a central hole, T, in said bell, and through the sleeve R into the board A.

The striker mechanism is preferably covered 70 by a small cap, U, by screws passed through projecting flanges V at diametrically-opposite sides of the cap U. A notch, Z, is made in the edge of the bell-cap U, through which the striker-arm or pendulum passes, and in which 75 it oscillates or vibrates when operated.

The knob may be turned either way, and when so turned will turn the spindle H and the scape-wheel I, secured to said spindle. The teeth of the scape-wheel engage the pallet N and impart oscillating motion to the 80 striker.

Having described this invention, what we claim, and desire to secure by Letters Patent, 85 is—

1. The combination, with the base or board having the bearing-plates supporting the knob, and the knob-spindle provided with the scape-wheel, and the pallet within the cap, having the striker-arm, with the hammer at its lower end connected to the pallet-shaft, 90 the said pallet being in engagement with the scape-wheel, of the alarm-bell secured upon the outer end of the sleeve by a screw passed through the alarm-bell and sleeve into the 95 base or board, substantially as specified.

2. In a door-bell, the combination, with the
rotary knob and its shaft carrying a scape-
wheel, of a pallet working on said scape-wheel
and carrying rigidly secured thereto a striker-
5 arm, and a bell within which the hammer end
of the striker works, the whole supported in
a base or bearing adapted to be attached to a
door, substantially as specified.

In testimony whereof we affix our signatures
in presence of two witnesses.

THOMAS M. BALES.
S. O. LEESON.
